[57] CLAIM

The ornamental design for a medication organizer, as
shown and described.

DESCRIPTION

FIG. 1 is an isometric view of one embodiment of a
medication organizer showing my new design;

FIG. 2 is a left side elevational view thereof;

FIG. 3 is a top plan view thereof;

FIG. 4 is a front elevational view thereof;

FIG. 5 is a bottom plan view thereof;

FIG. 6 is rear elevational view thereof;

FIG. 7 is an isometric view of another embodiment of a
medication organizer showing my new design;

FIG. 8 is a left side elevational view thereof;

FIG. 9 is a top plan view thereof;

FIG. 10 is front elevational view thereof;

FIG. 11 is bottom plan view thereof; and,

FIG. 12 is rear elevational view thereof.

In each of the two embodiments illustrated in the draw-
ings, the right side is a mirror image of the left side.*FIG_1*
